MOTOR-DRIVEN SWITCHING MECHANISM

John F. Toomey, Floral Park, N. Y., and Ralph L. Cordell, Tulsa, Okla.

Application June 18, 1947, Serial No. 755,274

5 Claims. (Cl. 175—375)

(Granted under the act of March 3, 1883, as amended April 30, 1928; 370 O. G. 757)

1

This invention relates to a switching mechanism and more particularly to a motor driven switching mechanism in which the switching elements are sufficiently rugged to withstand severe shock without false operation and in which the contacts are mechanically locked in an operated position.

It has been the general practice heretofore in switching mechanisms to provide an arrangement in which the operation of the switching elements is caused by the energization of an electromagnet or solenoid and in which the switching elements are maintained in the operated position by a mechanical latch. Such devices are inherently not well adapted to withstand the impact of a blow or sudden acceleration or deceleration without injury or false operation of the contacts.

The device of the present invention possesses all of the advantages of the prior devices and none of the foregoing disadvantages by reason of the novel arrangement of parts and structure as will appear more clearly as the description proceeds.

The operation of the device of the present invention differs from the principle of operation of the prior devices principally in the means employed for operating the switching contacts and in the rugged construction and stacked arrangement of the leaf spring switching contacts whereby operation of the switching contacts is prevented in response to shocks received by the device.

In accordance with a preferred embodiment of the invention the contacts are actuated to the operated position thereof by a rotatable member in threaded engagement with a nonrotatable member whereby axial movement of the nonrotatable member sufficient to actuate the contacts is effected by the operation of an electric motor in response to a momentary flow of operating current thereto. The threaded members maintain the contacts in an operated position until the motor is reversed by a momentary flow of current in the opposite direction through the motor. A rugged structure is thus provided which is well adapted to fulfill the objects of the invention and withstand severe shocks and sharp changes in acceleration or deceleration without false operation of the contacts.

The device is particularly adapted for use with ordnance devices which are subject to violent shocks or changes in acceleration or deceleration such, for example, as assault boats of the type claimed in the copending application for Demoli-

2

tion system of E. M. Brown et al., Serial No. 584,996, filed March 26, 1945.

One of the objects of the invention is to provide a new and improved self-locking switching mechanism which is sufficiently rugged to withstand severe shocks and changes in acceleration or deceleration without false operation of the contacts or injury thereto.

Another object is to provide a motor driven switching mechanism adapted to close and lock a plurality of switching elements in response to a momentary flow of current through the motor.

Still another object is to provide a new and improved motor driven switching mechanism adapted to close a plurality of control circuits in response to a momentary flow of current through the motor and maintain the contacts closed until the motor receives a momentary flow of current in the opposite direction.

Still other objects, advantages and improvements will be apparent from the following description, taken in connection with the accompanying drawing, of which:

Fig. 1 is a circuit diagram of the complete device according to a preferred embodiment thereof; and

Fig. 2 is a view in elevation of an alternative form of the device.

Referring now to the drawing for a more complete understanding of the invention on which like numerals of reference are employed to designate like parts, and more particularly of Fig. 1 thereof there is shown thereon a complete switching mechanism and control circuits therefor adapted to close a plurality of external control circuits as the mechanism operates in response to a momentary flow of current through the motor M. The motor is of the direct current reversible type such, for example, as the type disclosed in the aforesaid application of E. M. Brown et al. for Demolition system in which the motor field is obtained from a permanent magnet and the direction of rotation of the motor is controlled by the polarity of the voltage applied thereto.

The motor is provided with a shaft extension 9 threadedly in engagement with a member 10 adapted to be moved axially in either direction along the shaft selectively in accordance with the direction of rotation of the motor. The member 10 is, of course, restrained from rotative movement in any well known manner during rotation of the shaft as by the pin 11 along which the member 10 is adapted to move. The member 10 is thus adapted to be moved into engagement

55 with a follower 12 when the motor has been set

in operation and thereby close pairs of contacts 13, 14 and 15 respectively and disengage the normally closed pair of contacts 16.

The contact pile or stack comprising the pairs of spring leaf contacts 13, 14, 15, and 16 may generally be constructed and arranged in accordance with conventional telephone practice. It will be understood, however, that for the purpose of the present invention wherein the switching mechanism is employed in a demolition system which may be subjected to severe shocks such, for example, as those caused by demolition and countermining explosions, the spring leaf contacts are constructed of sufficient ruggedness and stiffness to prevent operation thereof in response to such shocks. By reason of the great mechanical advantage of the motor driven screw drive for the contacts, however, the motor requires only a small amount of energy to actuate the contacts notwithstanding the requirement that the contacts be sufficiently rugged to prevent false operation thereof.

The motor control circuit preferably includes a starting relay R adapted to be operated in response to the closure of a starting circuit at the switch 17 thereof associated with the starting element 18. The motor control circuit also includes a relay R1 adapted to be operated in response to the closure of switch 19 within a control element 21 and thereby cause a momentary flow of current in a reverse direction to the motor sufficient to operate the motor reversely and restore the switching mechanism to the original unoperated condition.

The operation of the device will best be understood by consideration of an assumed example. Let it be assumed, by way of example, that the switching mechanism of Fig. 1 is employed to control the arming circuit of the aforementioned patent application for Demolition system of E. M. Brown et al. and that the switch 17 of the starting element 18 is adapted to be closed in response to a signal received from a control station (not shown). Let it further be assumed that the switching mechanism is in the normal unoperated position illustrated on the drawing and that the assault boat is about to attack the target. The closure of switch 17 in response to a signal from the control station closes the starting circuit from battery BA by way of conductor 22, switch 17, conductor 23, winding of relay R, conductor 24, contacts 16 of the switching mechanism and thence by way of conductor 25 to ground thereby causing relay R to operate. As relay R operates, a circuit is closed from the positive terminal of battery BA1, conductor 26, make contact and armature 27 of relay R, conductor 28, winding of motor M, conductor 29, armature 31 and make contact of relay R and thence by way of conductor 32 to the grounded negative terminal of battery BA1 thereby causing the motor M to be set in operation in a direction to move the member 10 outwardly therefrom and close contacts 13, 14 and 15 and disengage contact 16 immediately thereafter. As contacts 16 are disengaged, current is removed from the winding of relay R thereby causing relay R to release and at armatures 27 and 31 thereof interrupt the operating circuit of the motor M. The motor M now comes to rest with the element 10 thereof maintained outwardly by reason of the threaded engagement thereof with the shaft 9 thereby locking the switching contacts in an operated position. As contacts 14 are engaged, a circuit is closed by way

of conductors 33 to the firing control apparatus and, in like manner, the closure of contacts 15 closes a circuit by way of the conductors 34 to the firing control apparatus. The conductors 33 and 34 may be conveniently employed to control the arming of a firing circuit as the contacts 14 and 15 respectively associated therewith are closed.

The firing control apparatus may be of any well known type suitable for the purpose in which the firing is accomplished by closing a circuit from a source of electrical potential to an electroresponsive detonator thereby to fire a main explosive charge (not shown). This is usually accomplished over a direct circuit from the source of potential to the detonator or, if desired, an amplifying unit may be employed to increase the strength of the firing signal and thereby fire the detonator in response to a signal of relatively weak strength received by the firing control apparatus, in which latter case contacts 14 and 15 may be employed to close circuits from the A and B batteries to the amplifying unit. Still another satisfactory arrangement is to employ the switching mechanism of the present invention for controlling the starting and operation of an electrically wound arming clock such, for example, as the arming clock disclosed and claimed in the copending application of A. H. Schwarz and R. W. Wallace for Self-winding arming and sterilizing mechanism for a mine, Serial No. 538,174, filed May 31, 1944, in which the clock is wound at regular intervals periodically by an electric motor, it being merely necessary to include the control contacts 14 or 15, as the case may be, in the operating circuit of the motor. Obviously with this arrangement, the arming clock will not be set into operation until the control circuits thereto are closed by the switching mechanism of Fig. 1.

The switching mechanism may be restored to the initial unoperated condition as shown on Fig. 1 at any time desired such, for example, as just prior to setting the assault boat of the foregoing example into operation, by operating the switch 19 of the control element 21. Let it now be assumed for the purpose of description that the switching mechanism is in the operated position and it is desired to restore it to an initial unoperated position. The closure of switch 19 applies battery BA2 to conductor 35, winding of relay R1, conductor 36, contacts 13 of the switching mechanism, from whence the circuit is continued by way of conductor 25 to ground thereby causing relay R1 to operate. The operation of relay R1 closes a circuit from the positive terminal from battery BA1 by way of conductor 26, make contact and armature 37 of relay R1, conductor 29, winding of the motor M, conductor 28, armature 38 and make contact of relay R1 and thence by way of conductor 32 to ground thereby causing current to flow through the motor M and operate the motor in a direction to withdraw the member 10 inwardly with respect thereto. As contacts 13 are disengaged during the inward travel of the member 10, the circuit to relay R1 is interrupted and relay R1 releases. As armatures 37 and 38 of relay R1 are moved sufficiently to disengage their respective contacts, the operating circuit to the motor M is interrupted and the motor M comes to rest with the member 10 thereof fully retracted. The switching mechanism is now restored to its original unoperated condition with contacts 16 thereof closed and the operat-

ing circuit of relay R in readiness to be energized by switch 17 of the starting element 18.

On Fig. 2 is shown an alternative form of the switch operating mechanism in which the motor M is arranged to make a predetermined number of free revolutions before the load is applied thereto. This is accomplished by extending the shaft 39 thereof and providing the end portion of the shaft with a spindle bearing 41 having a member 42 arranged for free rotation with respect thereto, means being provided for preventing endwise movement of the member 42 with respect to the shaft. The member 42 is provided with a threaded portion 43 in engagement with a complimentary threaded portion in the member 44. The member 44, it will be understood, is provided with any well known means for preventing rotative movement thereof while permitting axial movement in either direction in response to selective rotation of the member 42. The member 44 is adapted to close the spring assemblies of Fig. 1 in a similar manner to the member 10 of Fig. 1.

There is secured to the shaft 39 as by the pin 45 a member 46 having a pin 47 projecting therefrom substantially as shown. A washer 48 is mounted for rotation with respect to the shaft 39 intermediate the members 46 and 42 and provided with a pair of pins 49 and 51 disposed on opposite sides thereof and adapted to be engaged respectively by the pin 47 and a pin 52 arranged on the member 42.

When the motor has made substantially one revolution, the pin 47 is moved into engagement with pin 49 thereby causing the washer 48 to rotate. When the motor has made substantially one additional revolution the pin 51 of the washer 48 is brought into engagement with pin 52 thereby causing the member 42 to rotate. This arrangement may be defined herein as an acceleration drive in which the motor is permitted to make several revolutions before the load at the member 42 is applied thereto. This arrangement permits the use of a smaller motor than the arrangement of Fig. 1 and, if desired, may be employed in lieu of the motor arrangement of Fig. 1 for operating the switching elements of the device. Whereas in Fig. 2 a single free washer 48 has been illustrated, it will be understood that, if desired, additional washers may be employed whereby the motor may make several additional revolutions before the load is applied thereto.

The spring members 12, 13, 14, 15 and 16 are of strong low compliance construction and sufficiently rigid to withstand a severe shock or sudden change in acceleration or deceleration without falsely operating any of the contacts of the device and thus the device is reliable in operation even though the assault boat should be severely jolted by enemy fire while on its mission.

The device of the present invention may, if desired, also be used to arm or sterilize, as the case may be, mines, depth charges and the like, it merely being necessary to close the starting circuit to the relay R by any suitable means such, for example, as by a hydrostat, time clock or the like.

The switching mechanism may, if desired, be made slow operating whereby a predetermined time delay is effected between the closure of the motor operating circuit and the operation of the switching contacts. This may be accomplished in any suitable manner as by employing a reduction gearing between the motor and the member 11 or 46, as the case may be. Furthermore,

the motor may be employed to open a plurality of normally closed contacts or any combination of normally closed and normally open contacts during the operation of the device.

While the invention has been described with reference to two examples thereof which give satisfactory results, it will be understood by those skilled in the art, after understanding the invention, that various changes and modifications may be made without departing from the spirit and scope of the invention and it is intended, therefore, in the appended claims to cover all such changes and modifications.

The invention herein described and claimed may be manufactured and used by or for the Government of the United States of America for governmental purposes without payment of any royalties thereon or therefor.

What is claimed as new and desired to be secured by Letters Patent of the United States is:

1. In a switching mechanism of the character disclosed comprising a plurality of switching elements adapted to close a plurality of control circuits individual thereto, a reversible motor, means including an acceleration drive connected to said motor for operating said switching elements selectively in accordance with the direction of rotation of the motor as the motor operates, said acceleration drive comprising a driving member secured to the shaft of the motor, a driven member rotatively carried on said shaft, an actuating member threadedly carried on said driven member, means for preventing rotation of the actuating member whereby the actuating member is moved axially as the driven member operates, means for establishing a driving connection between said driving and driven members when the motor has made a predetermined number of free revolutions from an initial position of rest, and means controlled by one of said switching elements for causing a momentary flow of current in said motor sufficient to operate the switching elements.

2. A shock-proof switching mechanism of the character disclosed comprising a reversible motor having a threaded shaft, a member in threaded engagement with said shaft and having an eccentric bore therethrough arranged parallel to said shaft, a pin slidably arranged within the bore of said member and in fixed parallel relation with respect to said shaft whereby said member is moved in either direction along said shaft selectively in accordance with the direction of rotation of said motor, and a stack of strong low compliance leaf spring switching elements of sufficient rigidity to withstand countermine shocks received by the mechanism for preventing false operation thereof and supported in the path of travel of said member and adapted to be moved thereby into circuit controlling relation selectively in accordance with the direction of movement of said member along said shaft.

3. In a demolition system, a shock-proof switching mechanism of the character disclosed comprising a reversible motor having a threaded drive shaft, a member in threaded engagement with said shaft for movement along the axis thereof selectively in accordance with the direction of rotation of the motor when the motor is operated, a plurality of strong low compliance leaf spring switching elements of sufficient rigidity to withstand severe shocks for preventing false operation thereof and supported in spaced relation to each other and in the path of travel of the member for operation thereby selectively in

accordance with the direction of movement of the member along the axis of the motor shaft as the motor operates, and means for causing said motor to operate selectively in either direction.

4. In a demolition system, a shock-proof switching mechanism for operating a plurality of control circuits in said system and comprising a reversible motor having a threaded shaft, a member threadably carried on said shaft and movable in either direction along the axis thereof selectively in accordance with the direction of rotation of the motor, a plurality of strong low compliance leaf spring switching elements individual to said control circuits and of sufficient rigidity to withstand severe shocks for preventing false operation thereof and supported in predetermined spaced relation with respect to each other and transversely of said member in the path of movement thereof whereby the switching elements are operated by the member selectively in accordance with the direction of movement of the member as the motor operates, and means for operating the motor selectively in either direction.

5. A shock-proof mechanism of the character disclosed comprising, in combination, a reversible motor having a shaft, an acceleration drive comprising a first member secured to the shaft and having an eccentrically disposed arm extended therefrom parallel to the axis of the shaft, a second member rotatively supported on the shaft and having a pair of eccentrically disposed arms extended therefrom on either side thereof and parallel to the axis of the shaft, one of the arms of said second member being extended into the path of travel of the arm of said first member so as to be engaged thereby as the first member rotates with the shaft thereby to drive the second member from the motor, and a third member

5
